[57] CLAIM

The ornamental design for an electronic tennis game
housing, as shown and described.

DESCRIPTION

FIG. 1 is a top plan view of an electronic tennis game
housing showing my new design;
FIG. 2 is a front elevational view thereof;
FIG. 3 is a rear elevational view thereof;
FIG. 4 is a right side elevational view thereof (the left
side being a mirror image thereof); and
FIG. 5 is a bottom plan view thereof.

FIG. 1.

FIG. 2.

FIG. 3.

FIG. 4.

FIG. 5.
